UNITED STATES PATENT OFFICE

HENRY E. BARROLL, OF CHICAGO, ILLINOIS, ASSIGNOR TO HENRY E. BARROLL & CO., INC., OF CHICAGO, ILLINOIS, A CORPORATION OF NEW YORK

BOTTLE

Application filed October 13, 1926. Serial No. 141,267.

My invention relates to improvements in containers such as bottles, jugs, cans and the like, and has for one object to provide a new and improved pouring lip or spout with which a round and removable cap or cover may be used, and wherein the internal shape may be provided with an internal corking or sealing feature. One of the objects of my invention is to provide such a container wherein I am able to combine a round outer bearing neck surface and a round inner cork or seal engaging passage, and between them an oblong pouring lip, and wherein the outer round cap, when in place, incloses the lip and protects it against the deposit of dirt and the like. Another object of my invention consists, when employing any type friction outer cap such as the ordinary Crown cap, in providing the container with the fulcrum on which to pry off said cap with any ordinary tool, instead of using a special opener.

My invention is illustrated more or less diagrammatically in the accompanying drawings, wherein

25 Figure 1 is a side elevation of a jug according to my invention;

Figure 2 is a detailed section through the neck of the jug showing a cork in place of the cap;

30 Figure 3 is a plan view with cork and cap removed;

Figure 4 is a section through the neck showing the cap in place;

Figure 5 is a section similar to Figure 4 showing the cap in place before it is fastened;

Figure 6 is a side elevation in part section of a can to which my neck and spout is attached.

40 Like parts are indicated by like characters throughout.

A is a jug having a neck portion A¹, a jug handle A². Projecting upwardly from the jug handle is an anvil A³ adapted to serve as a support for the cap removing tool. A⁴ is the cap.

The upper end of the neck of the jug is surrounded by a cylindrical surface B. The cap is preferably made of a metal layer B¹, an inner tapered packing B², and an ac-

cordion-shaped neck extension B³, which when first assembled with the jug is in the position and shape shown in Figure 5. When the parts of the accordion as at B³ are collapsed as at B⁴ in Figure 4, the cap grips 55 the neck of the jug, locking the cap secured on the neck, to hold the cap in place.

C is a cylindrical passage through the neck of the bottle, inclined to the axis of the bottle and inclined to the surface of the cap. The 60 arrangement of this inclined passage provides a lip as at C¹ for pouring. When a cork is used, the cork C² goes in as indicated in Figure 2 in a direction parallel with the axis of the passage C but inclined to the axis of the bottle. This lip, when the cap is used, is completely inclosed. The relation between the neck and the bottle is such that a line tangent to the pouring lip and to the shoulder at the inner end of the neck is substantially tangent to the shoulder at the top of the bottle. Thus the bottle is provided from which material can be poured with a minimum of gurgling and air binding.

D is a can body, D¹ a neck mounted thereon in any suitable manner. This neck is outwardly expanded and terminates in a cylindrical top rim D². One side of the outwardly expanded neck, as at D³, forms an inclined pouring spout or lip. D⁴ is a cap 80 engaging the cylindrical neck of the spout and inclosing both the passage D⁵ through the neck and the pouring spout or lip.

It will be seen that the neck of the bottle shown in Figs. 1 to 4 has its upper cylindrical end portion to which the sealing cap is applied located eccentrically to the central longitudinal axis of the bottle, and that the pouring lip C¹ is in the side of the neck distant from such longitudinal axis of the bottle. This makes an arrangement that greatly facilitates pouring.

In the claims I have referred to a cylindrical portion about the upper edge of the neck. 95 It will be understood by the use of the term "cylindrical" I mean not only a cylindrical surface such as shown as B, but any generally cylindrical surface, as shown in Figure 6, which may have formed in it or upon it lock- 100

ing members such as the screw threads shown in Figure 6.

In the employment of the use of the term "pouring lip" I wish to mean a lip formed for the easy pouring of liquids wherein the lip is so shaped as to angle, sharpness of edge and the like, as to pour with a minimum tendency to spill or dribble. Referring for example to Figure 4 a pouring lip is shown at the left hand of the figure, whereas a flange not particularly shaped for pouring is shown at the right hand side.

I claim:

1. The combination, with a container, of a throat the axis of which is inclined to the axis of the container, the cross-section of the throat, in a plane perpendicular to the axis of the throat, being generally circular, the throat terminating at its upper edge in a flange having an upper surface lying in a plane inclined to the axis of the throat and generally perpendicular to the axis of the container the aperture bounded by such flange in such plane being non-circular, the exterior periphery of the flange being generally circular and being adapted to receive a circular cap or closure.

2. The combination, with a container, of a throat the axis of which is inclined to the axis of the container, the cross-section of the throat, in a plane perpendicular to the axis of the throat, being generally circular, the throat terminating at its upper edge in a flange having an upper surface lying in a plane inclined to the axis of the throat and generally perpendicular to the axis of the container the aperture bounded by such flange in such plane being non-circular, the exterior periphery of the flange being generally circular and being adapted to receive a circular cap or closure, the exterior of the flange being generally cylindrical and being adapted to receive a rim depending from such cap or closure.

3. The combination, with a container, of a throat the axis of which is inclined to the axis of the container, the cross-section of the throat, in a plane perpendicular to the axis of the throat, being generally circular, the throat terminating at its upper edge in a flange having an upper surface lying in a plane inclined to the axis of the throat and generally perpendicular to the axis of the container the aperture bounded by such flange in such plane being non-circular, the exterior periphery of the flange being generally circular and being adapted to receive a circular cap or closure, the pouring aperture bounded by the flange extending adjacent the outer edge to form a pouring lip.

4. A bottle having a neck terminating at its upper end in a generally cylindrical portion that is located eccentrically to the longitudinal central axis of the bottle and is adapted to receive a circular closure, there being

formed on the inside of the neck and at the portion thereof farthest from the longitudinal axis of the bottle, a pouring lip.

Signed at Chicago, county of Cook and State of Illinois, this 22nd day of September, 1926.

HENRY E. BARROLL.
